LIGHT RECORDING APPARATUS

Fred E. Wood, River Forest, and Horace Dawson,
Evanston, Ill.

Application March 26, 1938, Serial No. 198,338

2 Claims. (Cl. 273—101.1)

This invention relates to light recording apparatus and method.

An object of the invention is to provide a new method and means for recording upon a surface, at least for a limited period of time, a spot or area of light. A further object is to provide a luminous surface which will reproduce and maintain for a period of time the contour of a light spot or line, the surface being illuminated normally with light rays which do not, in any substantial degree, excite or activate the surface. A further object is to provide a light recording surface with means for briefly forming a light area thereon, the record of said light area being transitory. A still further object is to provide a target having a light-activatable surface, together with means for flashing a spot of light upon the target whereby the spot is recorded and made visible in its outline for a period of time. A further object is to provide improved mechanism for shooting from a distance an intensified beam of light upon a light-responsive target, said light shooting means being adjustable for changing the time of exposure, changing the area and contour of the light area, and in various other ways affecting the characteristics of the light flash and means of forming the same. Other specific objects and advantages will appear as the specification proceeds.

10 The invention is illustrated, in a preferred embodiment, by the accompanying drawings, in which—

Figure 1 is a side view in elevation of the light shooting device, the target, and illuminating device illustrating our invention; Fig. 2, a longitudinal sectional view of a portion of the light shooting device; Fig. 3, a broken longitudinal sectional view of the telescope barrel; Fig. 4, a transverse detail sectional view, the section being taken as indicated at line 4 of Fig. 2; Fig. 5, an enlarged detail view in elevation of means associated with the trigger for actuating the shutter; Fig. 6, a longitudinal sectional view of the structure shown in Fig. 5; Fig. 7, a longitudinal sectional view of the timing device employed; and Fig. 8, a broken transverse sectional view of the target or light recording device employed.

In the illustration given, A designates a light shooting device; B, a light recording device; and C, an illuminating device.

The device for throwing the light spot may be of any suitable construction. Any means for creating a light of sufficient intensity and for directing the beams therefrom so as to form a spot or light area of the desired contour may be

employed and it is obvious that this means may take a large variety of forms. The light flash or illumination may be formed by an incandescent bulb, a flash bulb of the type used in photographic methods, a mercury light, an arc light, a light formed by combustion of powder or other materials, etc. For the purpose of illustration, we have shown but one means for forming the desired light beam.

In the illustration given, the light shooting device A comprises a frame 10, generally in the form of a rifle. It will be understood that the frame may be in the form of a pistol, revolver, or any other suitable or desired shape or form. In the frame 10 there is supported a barrel 11 provided at its rear side with a closure member 12 through the central part of which is formed a minute opening 13. In actual practice, the opening 13 is much smaller than that shown in the drawings, the hole being exaggerated in the drawings for the purpose of illustration. In the forward end of the barrel 11 is mounted a thin inner barrel 11a carrying a lens 14 which may be of any suitable form or construction for directing the light rays to form an object of a desired contour. The particular lens illustrated is so correlated with the opening 13 and with the length of the scope to throw a small spot of light some thirty feet away.

In the specific illustration given, the two-part lens shown is secured in position within tube 11a by means of a threaded collar 15 and a slight shoulder in tube indicated by the numeral 16. It will be understood that the lens 14 may be modified in shape and structure in a great variety of ways so as to produce a spot of light at a desired distance or an area of light of any desired contour. Secured to the lower part of the barrel 11a by spot welding, screws, or other suitable means, is a rack 17 extending through a longitudinal slot in barrel 11 and which is engaged by a toothed wheel 18 accessible through an opening in the forward part of casing 10. By use of a small instrument, the wheel 18 can be rotated so as to shift the lens closer to or away from the aperture so as to permit proper form of spot of light when shooting from varying distances.

In the illustration given, we provide a light bulb support 19 just behind the rear portion of barrel 11, the support being secured upon the bracket 20 carried by casing 10. The support 19 is provided with a downwardly extending screw 21 threadedly engaging the knurled nut 22. Preferably, the reduced shank 23 of the bulb 55

support 19 is slidably carried within a sleeve 24 carried by the bracket 20, the reduced shank 23 being square in shape and being received within a square tube 24. Rotation of the nut 22 thus 5 raises or lowers the support 19 depending upon the direction of rotation of nut 22. Frame 20 can be moved from side to side on swivel 80. Friction holds it in place.

The light source illustrated is an electric light bulb 25. The bulb is secured within the mounting or holder 19 with the usual bayonet lock connection whereby the light bulb may be rotated a partial revolution within the holder 19 while yet making contact. Also, the holder 19 can be 10 rotated upon shank 23. We prefer to rotate the light bulb 25 so as to bring the two posts of the loop filament thereof almost in line with the opening 13 in member 12. The two strands are, however, slightly out of alignment so that the 15 direct rays from both posts pass directly into the opening 13, thus filling the opening 13 with light. The light filament 26 is shown more clearly in Figs. 2 and 4. With the structure shown, the light bulb 25 may be rotated while maintaining 20 its contact, while at the same time the entire supporting structure may be raised or lowered by manipulation of nut 22 and moved sideways by rocking frame 20 on swivel 80, all of which movements permit proper alignment of the filament posts and aperture 13. Above bulb 25 is a 25 swiveled closure 81 which may be opened to provide access to bulb 25.

Any suitable means may be employed for permitting the light rays to pass through the opening 13. If desired, the opening 13 may be left unprotected and the light beam caused by simply turning current on and off so as to flash the bulb 25. We prefer, however, to illuminate bulb 25 before permitting the light rays to pass therefrom through opening 13, thus building up the intensity of the bulb to its highest point at the time the rays are permitted to be passed through opening 13. In the illustration given, this is accomplished by means of a shutter 27 which is 30 pivotally supported to bracket 28 at the point 29. The shutter is cut away at its upper face as indicated by the numeral 30, one portion of the shutter, however, entirely covering the opening 13. The lower portion of shutter 27 is provided with an extension 31 which is engaged by a 35 spring 32 normally urging the shutter to the left, as viewed in Fig. 4. Movement to the left, is, however, prevented by an actuating finger 33 of a sector member 34 which extends substantially at 40 right angles to the shutter 27. The shutter 27 is provided with a cam surface 35 which is engaged by the sector member 34 when the same is swung upwardly so as to swing the shutter 27 to the right, as viewed in Fig. 4, thus exposing 45 the opening 13 to the rays of light from lamp 25. As shown more clearly in Fig. 4, the sector member 34 is pivoted upon shaft 36 secured to one wall of the frame 10. A spring 37 is secured to frame 10 and to the lower portion of sector 34, as shown more clearly in Fig. 2, so as to draw 50 the lower part of the sector 34 to the left, as viewed in Fig. 2. For actuating the shutter, it is necessary to draw the sector 34 rearwardly against the force of spring 37, and this is accomplished through the medium of the long link arm 38.

The link arm 38 is pivotally connected to the lower end of lever 39 which is in turn pivoted upon frame 10. The upper end of lever 39 is 55 provided with a trigger notch 40. Notch 40 is

adapted to be engaged by a shoe member 41 urged downwardly by spring 42, the spring being carried by the slide rod 43, and the shoe member 41 being also pivoted upon the slide rod 43. The slide rod 43 is provided with a pin 44 which engages slots 5 in a hammer 45. The hammer 45 is pivoted at its lower end portion at 46, and the detent 47 extending from the lower portion thereof engages the trigger 40 in a well known manner, the trigger being provided with the locking notch 48. In 10 the illustration given, the stock portion of the frame 10 is provided with a slot 53 receiving the rear portion of the rod or plunger member 43, and the rod is guided by an apertured boss 54 carried by frame 10. 15

If desired, suitable means may be provided for controlling the movement of rod 43. In the illustration given, we have provided a dashpot or timing device consisting of a tube 52 into which the reduced stem 53 of rod 43 extends, the stem 53 being provided with a piston 54 at its inner end. A spring 55 urges the plunger toward its forward position. At the opposite end of the tube 52 is a head member 56 threadedly engaging the end of the tube and closing the same, the head being provided with a threaded extension receiving the screw 57, screw 57 being carried by the rotatable or adjustment disk 58. A gasket 59 formed of felt or other suitable material is centrally apertured to receive the threaded extension of head 56 and assists in controlling the release of air from the tube. When the disk 58 is screwed out partially, the expanding felt 59 permits air, which passes around the threaded screw 56, to escape rather freely, but when the screw 56 is extended inwardly, the felt 59 is compressed and air escapes less freely. The knurled disk 58 is exposed within a slot 60 formed in frame 10 whereby the operator may adjust the device from the exterior of the gun. The trigger 40 is provided with a spring 61 which normally draws it toward the position shown in Fig. 1. 30

The lever 39 and shoe 41 are preferably guided within a channel bracket 62 which is slotted at 63 in its lower wall to permit the projection 40 of lever 39 to extend therethrough. 45

Any suitable switch arrangement for illuminating the bulb 25 may be employed. In the illustration given, we provide a fixed contact member 64 at the top of the frame, and spaced forwardly of the contact 64 is a second insulated support 65 carrying a depending spring finger 66, the spring of the finger normally drawing it forward into contact with the member 64 to close the circuit. The spring 66 has a bottom extension which is adapted to be engaged by an insulated block or ledge 67 secured to the top of the rod or plunger 43. When the rod is in the position shown in Fig. 1, the ledge 67 holds spring 66 out of engagement with contact 64. 50 However, when the hammer 45 is retracted, the member 67 is drawn back and permits the contact to be formed. Suitable wire connections (not shown) form a circuit with the light bulb 60 whereby illumination of the bulb is produced when the contacts 66 and 64 come together. 55

In the operation of the specific form of light projecting device illustrated, the hammer 45 is first drawn rearwardly and thus by engagement with pin 44 retracts the plunger 43 against the force of the spring 55 in the tube 52. This movement draws the shoe member 41 back of the lever 39 so that it is in position to operate lever 39 when the plunger moves forwardly. At the same time, the lower extension 47 of the hammer 70

45 engages the trigger shoulder 49 and thus holds the hammer 45 in retracted position. At the same time, the rearward movement of the ledge 67 permits the spring contact 66 to engage 5 the contact 64, thus closing the circuit and illuminating the light bulb 25. When the trigger is pulled, the hammer 45 is released and the plunger 43 is drawn forwardly by spring 55. As the plunger moves forwardly, it carries the shoe 10 41 which engages the extension 40 of lever 39 swinging the top part thereof forwardly. This draws the long link member 38 in a rearward direction and tilts the sector 34 so that the operating extension 33 thereof engages the cam 15 surface 35 of the shutter 27 and swings it laterally against the force of spring 32. The lateral movement of shutter 27 exposes the opening 13 in the tube 11 so that light rays pass from the two filament posts through the opening and are directed 20 by the lens so as to form a tiny spot on the target some distance away. As the rod 43 moves forwardly, the speed movement being regulated by the passage of air from tube 52, the shoe member 51 finally trips over the extension 40 25 of lever 39 whereby lever 39 springs back to its initial position under the force of spring 37 secured to the lower end of sector arm 34 carrying the extension link 38. This movement releases shutter 27 and under the force of spring 32, it springs back to its initial position over 30 the opening 13.

It will be seen that the period of exposure of the light beam is controlled by the knurled disk 58, which in turn controls the escape of air from the tube 52. As already stated, the light bulb 25 35 may be adjusted vertically by means of the knurled disk 22 and may be rotated slightly within its socket while still making contact therein, so that the two post portions of the loop filament are almost in line with the opening, the two posts being slightly out of alignment whereby light rays from both pass through the opening. Also, adjustment of the lens with respect to aperture 13 is accomplished by rotating the toothed wheel 18 which engages the rack 17. A stop 32 holds lever 39 normally against the force of spring 37.

In setting out one means for projecting a light ray of high intensity, it is realized that such means is only one of a great number of apparatuses effective for this purpose. The intensity of the beam being projected and the projection thereof, the timing of the flash, various adjustment means operating in such apparatus, may 50 obviously be varied extensively. The purpose of the disclosure herein is to set forth one complete device for the purpose of illustration.

By using a light source giving an intense beam, and a filter therewith which permits only 55 rays which activate the luminous surface to pass through, such rays being within the visible or invisible portion of the spectrum, the luminous surface will respond markedly to such rays while responding in a much lesser degree and, by contrast, hardly noticeable degree to ordinary light 60 illumination. A violet or ultra-violet light bulb, etc., such as illustrated, may be used.

The light recording device B may be of any suitable construction. In the illustration given, 65 we provide a target sheet 68 received within a box casing 69 equipped with a hinged closure 70. When not in use, the hinged cover is kept closed to protect the target from exposure to light. In the illustration given, the target consists of a 70 cardboard backing 71 having preferably a white

surface provided with a luminous surfacing layer 72.

One seemingly insurmountable difficulty of using a luminous surface for recording a light where it is desired that the surface itself be 5 clearly visible, is that the light which is used to illuminate the target also activates it, with the result that the entire surface glows. Thus when a beam of light is thrown upon the target, it is difficult to form a record of the light unless the beam is of extreme brilliance. We have found that luminous surfaces may be employed which are selective in character; that is, they are not activated to any considerable extent by certain types of light rays while they are extremely sensitive and responsive to activation by other light rays. For example, we find that certain luminous paints when spread over a surface, such as 71, in combination with a clear lacquer, are not excited to any very noticeable 10 degree by red or green rays when the source of the light is several feet from the target, while they are extremely sensitive and are readily excited by other light rays. Such luminous compounds are well known and are in commercial 15 use. As examples, the sulphides of barium, calcium, zinc and strontium, containing as usual some impurities, will continue to glow after the removal of the illumination. The sulphide powders, combined with a colorless lacquer, are 20 applied to the surface of the cardboard backing 25 71. Any suitable markings may be formed on the target by using one of the powders for the background and another of the powders for forming the demarcation lines; or, if desired, a 30 black or other colored lacquer may be used. Where a target is formed, as shown in the illustration, the lines 73 may be formed by using a sulphide powder which is different in color from the particular powder used to form the backing 35 40 surface or, if desired, a black lacquer, etc., may be employed for this purpose. The several sulphides above mentioned differ in color so that one may be employed in contrast with another or with the others for forming a continuous 45 luminous surface with designs formed thereon in different colors. In view of the fact that luminous surfaces of many types having the properties of glowing after the removal of the illumination are well known, no attempt will be 50 made to exhaustively cover all of such types, it being sufficient to state that they are well known in the art. It will be observed that the bull's eye of the target is provided with luminous paint 55 for recording light spots thereon.

As already stated, we utilize the selective characteristics of the luminous surfaces for effecting an illumination of the object with one type of ray to which the target is not noticeably responsive, while forming by contrast the light spot or 60 area on the surface by means of another source of illumination which includes rays to which the luminous surface is readily responsive. Further, a dim light containing activating rays 65 may be employed, while using an intense beam containing activating rays for forming the light spot which stands out in contrast to the feeble activation of the entire surface. We find that the powders are not normally excited to any great extent by the rays of longer wave length. For 70 example, red light and green light do not excite the powders to any noticeable extent. Green excites luminosity but the degree is relatively small. Likewise certain shades of red, but slight excitation does not interfere. However, lights 75

having great actinic powers readily excite the surface. Ultra-violet rays and rays of short length cause the surface to glow actively after a very brief illumination therewith. White light 5 containing the rays of short wave length activates the surfaces.

Under strong light containing rays of short wave length, the better powders will be activated or excited instantaneously so that an exposure 10 of but a fraction of a second will bring about phosphorescence. Apparently the longer the exposure to light, the longer will phosphorescence last. Short exposures, as where a spot is formed on the target for a brief moment result in a glow 15 lasting from a minute to several minutes. Exposures lasting four or five minutes result in phosphorescence for several hours. With brighter beams and rays of greater power of activation, the duration is longer.

20 An interesting characteristic of the luminous surface is that there seems to be practically no tendency for the glowing portion to diffuse into the unexcited portion of the surface; that is, the excited portion will not, in turn, excite the 25 unexcited portion.

For excluding as much as possible light beams from various sources and for the purpose, as shown later, of flooding the target with a particular colored ray, we prefer to enclose the target 30 within a box or casing. If desired, the box may be quite deep so that light from the side is entirely excluded. We obtain good results by placing the target in the back end of a tube lined with black felt, the tube then being illuminated by a window (not shown) having a red filter and with a light bulb above the filter.

By flooding the target with a colored ray, such as red or, from a distance, green, which has little tendency to excite a glowing effect, we find that 40 ample illumination of the target is produced, while at the same time the target is directly responsive to white light or any combination of light including rays of short wave length so that spots formed by such light are immediately recorded by a glowing area on the target, the glowing area being coterminous with the light spot formed. Any suitable means for forming such illumination may be employed. In the simple apparatus illustrated, we provide a reflector 74 provided at its forward end with a color filter 75 of the desired color, such as, for example, red or green. The reflector is supported by a stand 50 76 and a light bulb 77 is supported within the reflector casing.

55 It will be understood that by employing a very intense ray to which the target is extremely sensitive, a light spot may be formed thereon while yet illuminating the target with ordinary light. In other words, by using a luminous surface which is very responsive to an intense ray or a ray of a definite wave length, a record may be made because of the preferential response of the target to such a ray even though ordinary illumination be employed. Furthermore, if desired, the 60 target may be placed in a substantially dark area, the outlines of the rings being formed by constantly luminous material, such as zinc sulphide mixed with radium, thus rendering the target lines visible in the dark.

70 In the operation of the specific illustrative apparatus disclosed, the target 68 is supported within the box 69 and illuminated by a ray of relatively long wave length, such as, for example, red or green. The light shooting apparatus is 75 then manipulated as already described for shoot-

ing a spot of light upon the target, the period of exposure being regulated as already outlined. A number of light spots may thus be formed to 5 form a target pattern. The spots will glow upon the target for a period of one to several minutes during which time the marksman may examine the group. By drawing a curtain about the target or otherwise darkening the target, the intensity of the light spots is increased. Thereafter, the light spots fade slowly away, becoming less and less distinct. We have found that the glowing light spots can be quickly quenched by bringing the red rays up to the target and passing the rays back and forth or in any way across the target. For example, we have taken 10 a red light bulb and quickly quenched the light spots by passing the light bulb back and forth 15 across the face of the target.

In the development of an intense light, we sometimes employ a transformer reducing the 20 voltage to that suitable for a small light such as illustrated, the small bulb permitting the light filaments to be placed close to the opening. Some small automobile lamps which have been developed for use with parabolic reflectors form 25 an intense light concentrated in a small area and having a large percentage of rays of short wave length which readily excite the luminous paint. By employing a higher voltage than that for which the tube is normally designed, we find that 30 a more intense light is produced and which is satisfactory. Photo flush bulbs form a large percentage of actinic rays or rays of short wave length and may be substituted for bulb 25. New lamps have recently been developed to take the 35 place of photographic flash bulbs and which produce an extremely brilliant light. These may be used with the ordinary voltage employed in cities and it is merely necessary to have the wire leading from the rifle or pistol, etc. provided 40 with a connection for engaging a socket in the wall.

Instead of employing a light bulb which is clear or colored violet, ultra-violet, or other colors whereby, as already described, for projecting 45 a ray or group of rays of a special wave length or a group of rays including short and long rays, as in the case of a clear bulb, it will be understood that any form of filter may be employed in conjunction with a clear bulb or other source 50 of light. Furthermore, it is well known that certain sources of light emit rays of preponderantly short wave length which activate luminous surfaces to a great extent. Through the use of such extremely short rays or such rays as greatly 55 excite the surface to luminosity, whether such rays are produced by a special source of light, through the use of filters or other means, and whether such rays be visible or invisible, it is found that luminous surfaces which are relatively poor in activation by light may nevertheless be employed effectively in recording such selected rays while at the same time being made visible by ordinary illumination. In other words, we either illuminate the luminous surface with 60 a special colored light which does not activate it to any substantial degree and then project light spots containing activating rays upon the surface, or else we use the other alternative of illuminating a luminous surface which is not reactive to any appreciable extent with ordinary light or with rather mediocre illumination and then project upon such a surface rays which greatly excite ordinary illumination in their power 65 to excite luminosity in the surface. 70

In the preparation of the target surface or the light recording surface, we find that a surface layer can be prepared which is poorly responsive to light by using smaller quantities of the powders already described with greater quantities of lacquer, etc., or by using the powders which are least excited by light rays to luminosity. The variations and changes here involved will be recognized by those skilled in the art.

10 By shooting invisible rays, the operation more closely simulates actual shooting with a rifle, since neither the bullet nor the ray are visible.

While in the foregoing specification, we have gone into details as to steps and means employed, 15 it will be understood that these may be varied widely without departing from the spirit of our invention. The foregoing detailed description has been given for clearness of understanding only, and no unnecessary limitations should be 20 understood therefrom, but the appended claims should be construed as broadly as permissible, in view of the prior art.

We claim:

1. In apparatus of the class described, a target member provided with a surface layer excitable by certain rays of light to luminosity, means for illuminating said target to render the entire target surface visible to the eye by light rays which

illuminate but do not substantially excite said surface to luminosity, and a light discharge means in the shape of a firing iron adapted to be held in the hands of the user at a spaced distance from said target for momentarily projecting a 5 confined beam of rays of a type adapted to excite said layer to luminosity upon a spot on said target layer to cause said spot to become luminous against a non-luminous but visible target background. 10

2. In apparatus of the class described, a target member provided with a surface layer excitable by certain rays of light to luminosity but nonexcitable by certain illuminating rays, means for illuminating said surface layer to render it visible to the 15 eye solely by light rays which illuminate but do not substantially excite said surface to luminosity, and light projecting means adapted to be held in the hands of the user at a pre-determined distance from said target for projecting a concentrated beam upon a relatively small area upon 20 said illuminated but non-excited surface, said concentrated beam consisting of rays which excite said small area to luminosity to render the same visible against a non-luminous background 25 provided by the remainder of said surface layer.

FRED E. WOOD.
HORACE DAWSON.
